CLAIM

The ornamental design for a combined key chain with hockey puck transparent pendant containing a laser-induced logo, with LED light, as shown.

DESCRIPTION

FIG. 1. is a front perspective view of a combined key chain with hockey puck transparent pendant containing a laser-induced logo, with LED light showing my new design;

FIG. 2. is a top elevation view thereof;

FIG. 3. is a bottom elevation view thereof;

FIG. 4. is a front elevation view thereof;

FIG. 5. is a rear elevation view thereof; and,

FIG. 6. is a left side elevation view, the right side elevation view being the mirror image thereof.

The broken line showing of Logo in FIGS. 1-6 are for the purpose of illustrating a laser-induced image only and form no part of the claimed design.
